UNITED STATES PATENT OFFICE.

CLAES WILLIAM BOMAN, OF BROOKLYN, NEW YORK, ASSIGNOR TO EAGLE PENCIL COMPANY, OF NEW YORK, N. Y., A CORPORATION.

PENHOLDER.

No. 820,907.

Specification of Letters Patent.

Patented May 15, 1906.

Application filed March 15, 1906. Serial No. 306,195.

To all whom it may concern:

Be it known that I, CLAES WILLIAM BOMAN, a citizen of the United States, residing in the city of Brooklyn, county of Kings, State of New York, have invented a new and useful Improvement in Penholders, of which the following is a specification.

The object of the invention is to provide in a cheap and efficient way the stick or handle of a penholder at its front end with a projecting ink-shield and finger-rest.

To this end the invention consists of a penholder constructed as I shall now proceed first to describe in connection with the accompanying drawings and then to point out more particularly in the claim.

In the drawings, Figure 1 is a perspective view of the penholder. Fig. 2 is a longitudinal axial section of the same. Fig. 3 is a view of the three parts of which it is composed. Figs. 4 and 5 are sectional views of modified forms of shield.

A is the stick or handle of the penholder, made, preferably, of wood. B is the metallic "tip," so called. C is the shield. These are the three parts of which the penholder is composed.

The handle A is bored out axially at its front end for a portion of its length, as at a, the diameter of the bore a being such as to snugly accommodate the tip B, which is designed to be inserted in it and to be there held by glue or the like.

The metallic tip B consists of a sheet-metal tube b, having a flare or annular flange b' at its front end and containing a split spring-metal thimble b², between which and the tube b the pen P is inserted.

The shield C may be of any suitable material—such as cork, hard rubber, soft rubber, metal, &c. It is a narrow ring or annulus, preferably of bulbous exterior, as seen in Fig. 1. It is represented in Fig. 1 as being made of sheet metal of concave-convex cross-section. It may, however, have a protuberant rounded exterior only, with a straight cylindrical bore, as seen at C' in Fig. 4. In any

event it is intended to fit upon the cylindrical stem of tip B to be held between the flange b' thereon and the front end of handle A. If 50 desired, the annular shield may have a rounded flaring exterior, which at its outer end will extend beyond the seat against which the flanged end of the tip is designed to bring up, as seen at C', Fig. 5.

To put the penholder together, the shield C is fitted on the tip B and the latter is inserted in the hole in the front end of the handle A and pushed back as far as it will go—that is to say, as far as permitted by the annular shield C, which will bring up against the front end of the handle and be held tightly between the same and the flanged front end b' of the tip. As before said, glue may be used to secure the tip and handle together, and the 65 same instrumentality can be used, if desired, to hold the ring C tight on the tip.

The pen is simple and easily and cheaply made and is most effective for the purpose for which it is designed. The shield is, in 70 fact, a bulbous comparatively narrow annular protuberance at the front end of the handle, which limits the extent to which the tip can be inserted in the handle, which serves as a finger rest and shield, and which also, when 75 the penholder is laid down on the table, will keep the pen from contact therewith.

What I claim herein as new, and desire to secure by Letters Patent, is—

A penholder, consisting of the handle A 80 having bore a, metallic tip B adapted to be inserted and held in said bore, and provided with flanged front end b', and the annular bulbous shield C, fitted upon the shank of the tip, and confined between the flanged end of 85 said tip and the front end of the handle, as hereinbefore shown and described.

In testimony whereof I affix my signature in presence of two witnesses.

CLAES WILLIAM BOMAN.
